UNITED STATES PATENT OFFICE.

NATHAN H. DAVIS, OF PHILADELPHIA, PENNSYLVANIA.

TRUSS.

SPECIFICATION forming part of Letters Patent No. 678,379, dated July 16, 1901.

Application filed August 11, 1900. Serial No. 26,617. (No model.)

To all whom it may concern:

Be it known that I, NATHAN H. DAVIS, a citizen of the United States of America, residing in the city and county of Philadelphia, in the 5 State of Pennsylvania, have invented a certain new and useful Improvement in Trusses, of which the following is a true and exact description, reference being had to the accompanying drawings, which form a part thereof.

10 My invention relates to the construction of trusses, and is especially intended for the manufacture of trusses adapted for use as brake-beams or car-bolsters, though of course it is also adapted for other uses.

15 The object of my invention is to provide a truss of great simplicity of construction and one having very few detachable parts. In my former patent, No. 574,887, of January 12, 1897, I have shown and described a truss made 20 from an iron beam longitudinally slit intermediate its ends and then spread into truss form by upsetting one of the divided portions in order to shorten it and at the same time drawing away the other divided portion, the 25 two portions thus spread apart being stayed in position by a strut.

30 My present invention consists in a truss which, like my patented truss, is made from a beam longitudinally slit in the same manner, but in which in place of upsetting one of the divided portions I effect a similar shortening by bending or corrugating the one portion, the other portion being spread or drawn out in the same manner as in my former invention.

35 A further feature of my present invention consists in inclosing the corrugated or bent portion of the truss with a metal head, preferably of metal cast upon the said portion of the bar, such a head staying or bracing the bent or corrugated portion, so that it is as 40 strong as any other portion of the truss, and a strut separating the spread portions of the truss is preferably formed with or connected 45 to such metal head.

Reference being now had to the drawings which illustrate my invention, Figure 1 is an end view of an I-beam such as I prefer to use in the construction of my truss, Fig. 2 50 being a side elevation of such a beam. Fig. 3 is a side elevation of the beam with a longi-

tudinal slit formed in it. Fig. 4 is a side elevation of the beam bent into the form of the truss; Fig. 5, a side elevation indicating a modification in the character of the bend 55 or corrugation. Fig. 6 is a side elevation showing my truss supplied with a cast-metal head surrounding the bent portion. Fig. 7 is a cross-section on the line 7 7 of Fig. 6. Fig. 8 is a side elevation of the center of the 60 truss, showing the employment of a separable head in place of a head cast upon the truss; and Fig. 9 is a cross-section on the line 9 9 of Fig. 8.

A indicates the beam of which the truss is 65 made, having preferably the form of an I-beam, A¹ indicating the central web, and A² and A³ the upper and lower flanges of the beam.

B indicates the slit made longitudinally in 70 the beam and extending from the two points b b, a² indicating the portion of the beam lying above the slit and a³ the portion lying below it.

C is a bend or corrugation formed in the portion a² of the beam in order to shorten it 75 when the lower divided portion a³ is drawn out and away from the portion a², as indicated in Figs. 4, 6, and 8. The direction in which the bend or corrugation C is made is not of the essence of my invention, and the beam 80 may be bent in any convenient manner—as, for instance, as shown in Fig. 5, where it is bent upward, as indicated at C'.

D, Fig. 5, is a cast-metal head surrounding 85 the bent portion C' and having extending from it a strut, (indicated at D'.) D², Figs. 6 and 7, also indicates a cast-metal head cast upon the bent portion C of the truss-beam and having a strut D' extending from it and connecting, as indicated at d², with the spread division a³ of the beam.

D³ D³, Figs. 8 and 9, indicate divisions of 90 a separable head, which may be of either forged or cast metal and which are bolted together, so as to inclose and hold the bent portion C of the truss.

d' d' indicate truss extensions of the head divisions; E E, bolts holding the divided heads and struts together.

It will be obvious that a truss constructed 100 as above described is one of great strength and at the same time one having the minimum

number of separable parts and one which is constructed with great ease.

Having now described my invention, what I claim as new, and desire to secure by Letters 5 Patent, is—

1. A truss formed of a beam of metal slit longitudinally intermediate its ends and having its divided portions spread apart and one said portion so corrugated or crimped as to in 10 effect shorten it relatively to the other, said divided and spread portions being held in relative position by a strut.

2. A truss formed of an I-beam of metal slit longitudinally intermediate its ends and 15 having its divided portions spread apart and one said portion so corrugated or crimped as to in effect shorten it relatively to the other, said divided and spread portions being held in relative position by a strut.

3. A truss formed of a beam of metal slit longitudinally intermediate its ends and having its divided portions spread apart and one said portion so corrugated or crimped as to in 20 effect shorten it relatively to the other, in combination with a metal head secured to and inclosing the said corrugated or crimped por-

tion and a strut interposed between the spread portions of the bar.

4. A truss formed of a beam of metal slit longitudinally intermediate its ends and having 30 its divided portions spread apart and one said portion so corrugated or crimped as to in effect shorten it relatively to the other, in combination with a metal head secured to and inclosing the said corrugated or crimped portion and a strut interposed between the spread portions of the bar and extending from the metal head to the opposite spread portion.

5. A truss formed of a beam of metal slit longitudinally intermediate its ends and having 35 its divided portions spread apart and one said portion so corrugated or crimped as to in effect shorten it relatively to the other, in combination with an integral cast-metal head inclosing the said corrugated or crimped portion and a strut interposed between the spread portions of the bar.

NATHAN H. DAVIS.
